DART

Arthur B. Mull, Chicago, Ill., assignor of one-half to Spotswood Specialty Company, Inc., Lexington, Ky., a corporation of Kentucky

Original application July 23, 1941, Serial No. 403,701. Divided and this application November 4, 1941, Serial No. 417,819

7 Claims. (Cl. 273—106.5)

This invention relates to a dart and more particularly to a dart utilizing sheet material in the manufacture thereof.

An object of this invention is to provide a dart wherein the main body portion thereof is made from sheet material.

Another object of this invention is to provide a dart that is easily produced, economical to manufacture, efficient, dependable and safe to manipulate, wherein the dart is provided with a protective head.

Another object of this invention is to provide a paper dart having a suction cup attached thereto.

Another object of this invention is to provide a dart made from folded sheet material attached to a suction cup.

Other objects and advantages reside in the construction of parts, the combination thereof and the mode of operation, as will become more apparent from the following description.

In the drawing,

Figure 1 is a perspective view of the dart or projectile loaded in a catapult in readiness for firing.

Figure 2 is another perspective view showing a portion of the catapult and the dart shortly after leaving the catapult.

Figure 3 is a top plan view of the blank used in forming the main body of the dart.

Figure 4 is a rear end view of the dart or projectile.

Figure 5 is a perspective view looking at the side of the dart or projectile.

This is a divisional application of my copending application Serial No. 403,701 filed July 23, 1941, for Catapult, ripening into Patent No. 2,264,807 on December 2, 1941.

The catapult dart assembly shown herein consists broadly of a dart or a projectile and a catapult therefor, which will now be described.

The projectile or dart assembly includes a head portion, which consists of a vacuum or suction cup 10, and a tail portion 12. The tail portion 12 is made from suitable sheet material, as for example, a good grade of paper or light weight cardboard. The entire tail portion consists of a single piece made from a blank as shown in Figure 3. This tail portion includes a pair of side members 14 formed by folding the blank along the line 14a. The side members 14 merge into coplanar wing portions 16 extending outwardly from the creases or score lines 16a. The plane of the wing 16 is offset from the suction cup, so as to permit the use of a catapult for projecting the dart, as will appear more fully later.

As may be seen by referring to Figures 3 and 4, the tail portion is reenforced by an extension 18 that is folded on the score or fold line 20. This extension 18, when folded into the bight be-

tween the sides 14, forms a reenforcing portion for the neck 22 of the dart, which neck projects into a slotted opening or hole in the suction cup 10. The neck 22 is enlarged at the outer end, so as to form an anchor seated in the slot in the suction cup 10. Although the neck is enlarged and thereby anchored in the slot in the suction cup, it is necessary for some purposes to cement the neck 22 in the slot of the suction cup.

Instead of cementing the neck, a suitable reinforcing member may be wedged between the folded portions of the neck, so as to cooperate with the enlarged end to rigidly anchor the tail portion in the suction cup. This reenforcing member may project between the sides of the tail portion, so as to give the sides rigidity. The rear ends of the sides 14 are inclined at 14b, so as to form a band engaging seat, as will appear more fully later. This dart assembly is projected from a suitable catapult, which will be briefly described.

The catapult is preferably made from a cardboard blank 30 having a pair of overlapping portions or flaps 34 folded upon the main body portion 36 and held in position by a staple 38. The overlapping portions 34 cooperate to form a longitudinal slot 35 having a cross sectional area simulating an inverted T, in which slot the dart is seated immediately prior to being projected. The forward end of the main body portion is provided with an extension 40, having a pair of slots 42 adapted to receive a rubber band 44. Before loading, this rubber band is stretched so as to have the loop positioned under a band retaining extension 46 projecting from the opposite end of the catapult.

As clearly shown in Figure 1, when the rubber band 44 has been positioned in engagement with the extension 46, the dart is inserted in the slot formed between the overlapping portions 34 and the main body portion 36. The rubber band may then be released from the extension 46, causing it to snap into engagement with the band receiving portion of the dart, so as to shoot the dart from the catapult.

As soon as the dart leaves the catapult, the wings 16, extending outwardly, guide the dart, causing it to shoot through the air. The suction cup 10 functions as a weight and the tail portion 12 of the dart functions as a tail, causing the suction cup to head the dart. If the suction cup alights with sufficient momentum on a smooth surface substantially normal to its direction of flight, the suction cup will stick to the smooth surface, holding the dart in the position in which it alights.

This dart is easily manufactured from cheap

materials, requiring few parts that are assembled with a very few manual operations. At the same time, the resulting structure is very attractive as an amusement toy.

The type and grade of material used, the weight and the size thereof are a matter of choice, depending entirely upon the ultimate use to which the dart is to be put. Instead of using cardboard for the sheet material parts, these may be made from sheet metal or any other suitable sheet material having the desired characteristics.

Although the preferred modification of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A suction cup sheet material dart assembly for use in a catapult provided with a longitudinally extending slot having a cross sectional area simulating an inverted T, said dart including a rubber suction cup forming the head of the dart assembly, said rubber suction cup having a retaining slot, and a sheet material tail portion provided with a main body portion having the forward ends folded and attached in the slot in the suction cup, and outwardly extending coplanar wing portions integral with the main body portion to guide the dart assembly in flight, said outwardly extending wing portions being located in a plane positioned to one side of the suction cup so as to permit the dart to be loaded in the T slot of the catapult.

2. A suction cup sheet material dart assembly for use in a catapult provided with a longitudinally extending slot having a cross sectional area simulating an inverted T, said dart including a rubber suction cup provided with a retaining recess, said suction cup forming the head of the dart, a tail member having one end anchored in said retaining recess, and means for attaching said tail member in the suction cup, said tail member including a pair of integral side portions united in a fold along the top of the tail member, each of said side portions merging into a laterally extending wing portion, said wing portions guiding the dart in flight, said outwardly extending wing portions being located in a plane positioned to one side of the suction cup to permit loading of the dart in the T slot of the catapult.

3. A suction cup sheet material dart assembly for use in a catapult provided with a longitudinally extending slot having a cross sectional area simulating an inverted T, said dart including a rubber suction cup provided with a retaining recess, said suction cup forming the head of the dart, a tail member having one end anchored in said retaining recess, means for cementing said tail member in the suction cup, said tail member including a pair of integral side portions united in a fold along the top of the tail member, and means projecting into the retaining recess in the suction cup and positioned between said side portions for reenforcing said tail member, each of said side portions merging into a laterally extending wing portion, said wing portions being located in a plane positioned to one side of the

suction cup, said wing portions guiding the dart in flight.

4. A suction cup sheet material dart assembly including a rubber suction cup provided with a retaining recess, said suction cup forming the head of the dart, a tail member having one end anchored in said retaining recess, means for cementing said tail member in the suction cup, said tail member including a pair of integral sheet material side portions united in a fold along the top of the tail member, and reenforcing means located between the side portions of the tail member, said reenforcing means consisting of a sheet material portion folded on a transverse line so that the reenforcing means is integral with the side portions.

5. A suction cup sheet material dart assembly for use in a catapult provided with a longitudinally extending slot having a cross sectional area simulating an inverted T, said dart including a rubber suction cup forming the head of the dart, said rubber suction cup having a vertically disposed retaining slot, and a sheet material tail member including a pair of integral side portions united in a fold along the top of the tail member, said side portions merging into a restricted tapered neck portion, said neck portion projecting into the retaining slot in the suction cup, the tapered neck anchoring the tail member in the suction cup, each of said side portions merging into a laterally extending wing portion located in a plane positioned to one side of the suction cup and said wing portions guiding the dart in flight.

6. A suction cup sheet material dart assembly including a rubber suction cup forming the head of the dart, said rubber suction cup having a retaining slot, and a sheet material tail member including a pair of integral side portions united in a fold along the top of the tail member, said side portions merging into a restricted tapered neck portion, and folded reenforcing means positioned between said side members for reenforcing the tail member, said folded reenforcing means being integral with the neck portion, said neck portion projecting into the retaining slot in the suction cup, the tapered neck anchoring the tail member in the suction cup, each of said side members merging into a laterally extending wing portion, said wing portions guiding the dart in flight.

7. A suction cup sheet material dart assembly for use in a catapult provided with a longitudinally extending slot having a cross sectional area simulating an inverted T, said dart including a rubber suction cup provided with a retaining recess, said suction cup forming the head of the dart, a tail member having one end positioned in said retaining recess, means for attaching said tail member to the suction cup, said tail member including a dart of integral sheet material side portions united in a fold along the top of the tail member, said side portions merging into wing portions positioned in a plane located to one side of the suction cup, and reenforcing means overlapping the side portions of said tail member, said reenforcing means consisting of a sheet material portion folded on a transverse line so that the reenforcing means is integral with the side portions.
